UNITED STATES PATENT OFFICE

2,488,893

PLAY HORSE

Walter J. Barrett, Detroit, Mich.

Application December 5, 1945, Serial No. 632,911

1 Claim. (Cl. 272—53.2)

1

This invention relates to play horses and similar animal simulations which may be ridden by children and has for its object to provide such a device which may be very simply and economically constructed without sacrificing attractive appearance and strength and in which typically movable parts of the simulated animal may be caused to operate in a life-like manner as a result of general motion applied to the device as a whole by the rider.

More particularly, the said invention has for its object to provide a series of motion-imparting rods and links for operative attachment to the individual movable features of the device and so arranged and constructed that the assembled linkage may be readily mounted in the framework of the device as a unit and without requiring partial or individual assembly of parts within the framework or adjustment of such parts during or after assembly.

Still further, it is an object of the said invention to provide in such a device the simulation of an animal wherein the side members thereof are in the form of flat boards of suitable outline for the purpose of such simulation, and a unitary link structure for operating individually movable parts pivoted or hinged to or between said boards, with pivots for said linkage mounted or journaled in said boards in such manner that they may be readily matched with correctly positioned holes or bearings in the said boards, to permit ready mounting of the assembled linkage by the simple assembly of the boards in matching relation on opposite sides thereof in effecting the assembly of the body portions of the simulated animal.

Still further objects or advantages additional or subsidiary to the aforesaid objects, or resulting from the construction or operation of the said invention as it may be carried into effect, will become apparent as the said invention is herein-after further disclosed.

In carrying the said invention into effect, I may provide the novel construction and arrangement of parts hereinafter described, by way of example, having reference to the accompanying drawing, wherein:

Figure 1 is a sectional elevation of a device embodying the said invention; and

Figure 2 is a plan of the same.

Similar characters of reference indicate similar parts in both figures of the drawing.

The toy as illustrated is in the semblance of a horse constructed in general of flat boards, 10 and 11 being the sides of the body portion spaced by marginal members, 12, 13, 14 and 15, so dis-

2

posed as to provide openings at 16 and 17 as well as at 18 to accommodate certain movable parts hereinafter described.

19 and 20 represent the front and rear legs secured to the front and rear portions of the side members 10 and 11 of the body and mounted on the platform 21 which may be arranged to rock in any convenient manner and is simply shown in the drawings as being pivoted at 22 to side boards 10 23 of the base.

Carried between the said side boards 23 is a bracket 24 connected to an arcuate link 25, which may be of a springy nature and which at 26 is hinged to a rod 27 extending upwardly and then horizontally through the opening 17 of the body structure, the said rod 27 being pivoted at 28 and hinged at 29 to rods 30 and 31. The said rod 27 is also connected by a link 32 to a tail rod 33 pivoted at 34 in the openings 16 terminating in the representation of a tail 35.

Between the forward ends of the body boards 10 and 11 is the hollow structural form of head 36 movable on the hinge 37 and having a disk-like lower portion 38 rotatable in the opening provided at the forward ends of the members 12 and 15 of the body structure; and pivoted in the said head structure is a jaw member 39, pivoted at 40, the inner end of which member is hinged to the outer portion of the said rod 30.

The inner end of the jaw member 39 is also connected by rod 42 and crank 43 to a rocker shaft 44 passing laterally through the head structure and having the representation of ears 45 mounted on the ends thereof. Similarly, members 46 representing eyes rotatably journaled in the head structure are connected by the crank 47 and rod 48 to the outer portion of the said jaw member 39.

Intermediate of the body structure of the horse 40 is positioned the pivot 49 of a rocker 50, one end of which is hinged at 51 to the rod 31, hereinbefore referred to; and the other end at 52 to a further rod 53 hinged at 54 to the disk-like portion of the head structure 38 at a point remote from the pivot 37.

An examination of the linkage referred to will disclose that the rocking of the horse, by a child riding on any suitable seat or saddle which may be placed on the body portion thereof, will cause the rod 27 to rock on its pivot 28 and thereby, through the rod 31, operate the rocker 50 which, in turn, through the agency of the rod 53 will swing the head portion 36 of the device upwardly and downwardly about the pivot 37. The disk-like formation 38 will maintain a closure, during

such rocking motion, at the open end of the body portion of the device as will be readily observed.

At the same time motion of the rod 27 will be transmitted through the rod 30 to the rear portion of the jaw member 39, causing its opening and closing, and the motion will be further transmitted through the leaf springs 42 and 48 to the ears 45 and eyes 46 previously referred to.

The link 32 moved by the rod 27 will also rock the rod 33 on its pivot 34 thus providing movement for the tail member 35.

In assembling a device of this type, the members 25, 27, 30, 31, 32, 33, 50, 53 and 39 with the attachments 42, 43, 44, 46, 47 and 48 may be first assembled as a unit including the pivot members 28, 34, 49, 40 and 54, and the two side members of the head portion then assembled together with the pivot members 44 and 54 entering suitably positioned holes or bearings in the said side boards of the head structure; so that when the side boards and their spacing means are so assembled, and glued or otherwise secured together, the operating mechanism for a jaw 39, the eyes 46 and the ears 45, as well as the means for oscillating the head structure as a whole, will all be connected in operative relation without further connections or adjustments.

Similarly, the side boards 10 and 11 of the body portion of the device are also fitted over the pivots 28, 34 and 49, which is but a simple operation, following which the link 25 may be connected to the bracket 24 and the whole general structure mounted on the pivots 22 of the frame 23. The pivot 37 of the head structure is of course assembled into the side boards of the body structure during the assembly of that structure as will be quite obvious.

An arrangement such as that described provides a play horse, or such type of device, which is very attractive to children and in which the natural movement of various elements is secured without involving the use of gears, cams, slides and similar mechanisms calling for individual assembly or adjustment within the device, and is capable of withstanding extremely hard usage as the number of parts actually subjected to wear

are limited to the pivots and hinges described. Furthermore, undue shock which may be ordinarily imparted to the mechanism by violent usage may be greatly absorbed by the spring, bow-like form of the link 25.

This invention may be developed within the scope of the following claims without departing from the essential features of the said invention and it is desired that the specification and drawing be read as being merely illustrative of a practical embodiment of the said invention, and not in a strictly limiting sense.

What I claim is:

In a device of the class described, in combination, a simulated animal structure comprising a body portion having two spaced side walls having parallel opposed inner faces, a head portion also having two spaced parallel side walls pivotally mounted between side walls of said body portion, movable members in representation of anatomical details mounted in said head portion, mounting means providing for rocking of said device as a whole, a single lever fulcrummed in said body portion, a spring link connecting the lower end of said lever to a stationary part of said mounting means, and means linking the other end portion of said single lever with all movable parts of said device to effect their individual movement upon the actuation of said lever by the rocking of said device as a whole, said linkage means and said lever forming a structural assembly capable of installation in said body as a whole connected unit and solely supported by said side walls.
